US0D1082419S

(12) **United States Design Patent** (10) **Patent No.:** **US D1,082,419 S**
Bo (45) **Date of Patent:** **** Jul. 8, 2025**

(54) **TUMBLER LID**

(71) Applicant: **Anhui Inno-Sign International Co., Ltd.**, Anhui (CN)

(72) Inventor: **Jin Bo**, Anhui (CN)

(73) Assignee: **Anhui Inno-Sign International Co., Ltd.**, Anhui (CN)

(**) Term: **15 Years**

(21) Appl. No.: **29/970,542**

(22) Filed: **Oct. 29, 2024**

Related U.S. Application Data

(63) Continuation of application No. 29/936,984, filed on Apr. 11, 2024, now Pat. No. Des. 1,048,807.

(51) **LOC (15) Cl.** **07-02**

(52) **U.S. Cl.**

USPC **D7/392.1**

(58) **Field of Classification Search**

USPC D7/392.1, 392, 387, 391, 396.1, 396.2, D7/397; D9/434-436, 440, 446, 447, D9/449, 450

(57) **CLAIM**

The ornamental design for a tumbler lid as shown and described.

DESCRIPTION

FIG. 1 is a top perspective view of a tumbler lid showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are shown for the purpose of illustrating exemplary environmental subject matter and form no part of the claimed design.

1 Claim, 4 Drawing Sheets
